UNITED STATES PATENT OFFICE.

WILLIAM B. KING, OF BOSTON, MASSACHUSETTS.

GAS-BURNER.

1,253,604.

Specification of Letters Patent. Patented Jan. 15, 1918.

Application filed October 9, 1913. Serial No. 794,510.

To all whom it may concern:

Be it known that I, WILLIAM B. KING, a citizen of the United States, residing at Boston, in the county of Suffolk and State 5 of Massachusetts, have invented certain new and useful Improvements in Gas-Burners, of which the following description, in connection with the accompanying drawings, is a specification, like reference characters in 10 the drawings indicating like parts in the several figures.

This invention relates to incandescent gas burners and particularly to burner-caps such as are usually sold with the mantle.

15 There has been upon the market for some years a burner having a pilot-tube which is centrally located within the Bunsen-tube. This burner requires, however, a mantle with a special burner-cap having a central 20 opening through which the central pilot-tube can pass in order that the pilot-flame from the pilot-tube may ignite the gas to render the mantle incandescent when the special key on the burner is turned to allow 25 gas to enter the Bunsen-tube. Such a mantle is known in the trade as a "pilot-gauze" mantle and can not be used on burners not having a central pilot-tube because the Bunsen flame is liable to "flash back" through 30 the central opening. Considerable confusion has therefore resulted among the mantle-using public, owing to the non-interchangeability of the two types of burner-caps supplied with the mantles.

35 The object of the present invention is to provide, for sale with incandescent gas mantles, a burner-cap that can be installed and used upon either type of burner without any special thought or manipulation upon the 40 part of the user. For accomplishing this object, my invention consists broadly in providing means for preventing the flow of combustible mixture through the opening in the deflector in the burner-cap of a "pilot- 45 gauze" mantle so that it may be used on a regular burner having no pilot-tube and in constructing and arranging said means so as to allow the pilot-tube of an internal pilot-tube burner to pass through the opening in 50 the deflector if the burner-cap, with its attached mantle, is used on a burner having such a pilot-tube.

55 In carrying out my invention in its preferred form I provide the opening in the burner-cap with a closure of heat resisting but puncturable material which will remain

intact as long as the cap and mantle are used upon a burner having no pilot-tube, but which will be punctured by the pilot-tube during the simple and necessary act of placing the cap and mantle upon a burner having such a pilot-tube. 60

In order that the invention may be more fully understood, reference is hereby made to the accompanying drawings, of which— 65

Figure 1 is a side elevation, partly in section, of the present style of mantle fitted with the burner-cap having the central opening, with my improvement applied thereto and punctured by its positioning upon the 70 central pilot-tube burner, only the upper portion of which is shown, and

Fig. 2 is a similar view of the same mantle and shows the closure about to be punctured by bringing the burner-cap into its 75 proper location on the central pilot-tube burner.

The mantle 7 and burner-cap 8 are sold together as a single article of commerce, the two being held in fixed relationship by any 80 suitable means, as by the wire 9, as is well known by users of mantles. In the burner-cap the central part of the wire-gauze 10 is provided with a deflector which consists of a washer 11 having a central opening through 85 which a small tube 12 passes downward into the mixing chamber 13. The tube 12 is secured to the washer 11 and gauze 10 by being headed over on the washer 11 above the slight shoulder 14. The tube 12 is enlarged somewhat at its lower end in order 90 more easily to engage the central pilot-tube 15 when the burner-cap is placed in position on the top of the mixing chamber tube 18. When in position, the top of the pilot-tube 95 15 is about flush with the upper end of the tube 12, as shown in Fig. 1. The above is all well-known in the art and is here described in order that the application of my invention will be better understood. 100

A broad feature of my invention consists in closing the tube 12 with a heat resisting but puncturable material which will remain intact during shipment and during later use on a burner having no central pilot-tube, 105 thus making the burner-cap equivalent to that sold for use on such burners, but which material, when the mantle and cap are placed on a central pilot-tube burner, as seen in Figs. 2 and 1, will become punctured 110 without any special manipulation upon the part of the person who puts the mantle on

the burner and usually even without his knowledge that such an operation is taking place. The invention further consists in using a material which will not clog the 5 burner or pilot-tube in any way.

In its preferred form, the invention consists in closing the lower end of the tube 12 with a single layer of aluminum foil 17, which admirably meets all requirements of 10 the case. This foil is cut large enough to be folded and crimped upon the outside of the tube 12, as seen in Fig. 2, to secure it in position. When this foil extends a substantial distance upon the outside of the tube 12, 15 there is no danger of gas entering the tube (when the mantle is used on a burner having no central pilot-tube) and causing a series of miniature explosions even if the crimping is not gas tight. This is because the gas 20 pressure is comparatively low in the mixing chamber and a free outlet exists for the gas to pass through the gauze in the regular way.

It is to be understood that I do not limit 25 myself to the use of aluminum foil placed as described but foils of other metals may be used as well as any other suitable substance and the foil or substance may be otherwise located relative to the burner-cap 30 and it may be secured in any suitable manner without departing from the spirit of the invention.

Having thus described my invention, what 35 I claim as new, and desire to secure by Letters Patent, is—

1. A burner-cap having a gauze and a deflector, an opening in the deflector and a closure of heat resisting but easily puncturable material for said opening.
- 40 2. A burner-cap having a gauze and a deflector, an opening in the deflector and a closure of aluminum foil for said opening.
3. A burner-cap, for use on burners either with or without a central pilot-tube, having 45 a gauze, a deflector on the gauze, a tube securing the deflector to the gauze, a closure of heat resisting material for the tube to permit the use of the cap on burners of the second type, said closure being capable of 50 being punctured by the pilot-tube of burners of the first type by the positioning of the cap on said burner.
4. A burner-cap having a gauze, a washer

in the center of the gauze, a tube securing the washer to the gauze, and a closure for the 55 tube consisting of a heat resisting but easily puncturable material secured to the tube by crimping and folding.

5. A burner-cap having a gauze and a deflector, an opening in the deflector and a closure for said opening consisting of easily 60 puncturable material somewhat loosely secured to the deflector and forming a joint slightly open in places.

6. A burner-cap having a gauze and a deflector, an opening in the deflector and a closure for the opening consisting of easily 65 puncturable material, said closure being arranged below the gauze so as to be located in the stream of cool combustible mixture when 70 in use on a burner.

7. A burner-cap having a gauze and a deflector, an opening in the deflector and a closure of puncturable material for the opening, a burner having an internal pilot-tube 75 for puncturing said closure, said material being of such a nature that it will not clog the pilot-tube.

8. A burner-cap having, in combination, a gauze, a deflector, an opening in the deflector 80 and means for preventing the flow of combustible mixture through the opening in the deflector, said means being constructed and arranged to allow the pilot-tube of an internal pilot-tube burner to pass through the 85 opening in the deflector when the cap is placed on a burner having such a pilot-tube.

9. A burner-cap, for use on burners either with or without an internal pilot-tube, having a gauze, a deflector, an opening in the 90 deflector and means for preventing the flow of combustible mixture through the opening in the deflector to permit the use of the cap on a burner of the second type, said means being constructed and arranged to allow 95 the pilot-tube of a burner of the first type to pass through the opening in the deflector when the cap is placed on a burner of the first type.

In testimony whereof I have signed my 100 name to this specification in the presence of two subscribing witnesses.

WILLIAM B. KING.
